UNITED STATES PATENT OFFICE.

WILLIAM C. GHOLSON, OF CINCINNATI, OHIO.

WIRE-FENCE BINDER.

SPECIFICATION forming part of Letters Patent No. 352,406, dated November 9, 1886.

Application filed September 29, 1884. Serial No. 144,238. (No model.)

To all whom it may concern:

Be it known that I, WILLIAM C. GHOLSON, a citizen of the United States, residing at Cincinnati, in the county of Hamilton and State 5 of Ohio, have invented certain new and useful Improvements in Wire-Fence Binders; and I do hereby declare the following to be a full, clear, and exact description of the invention, such as will enable others skilled in the 10 art to which it appertains to make and use the same.

My invention relates to wire-fence binders used to tighten the wires and regulate their tension, whereby all sagging, cracking, and 15 bending of the wires is prevented; and it consists of a binder in three parts—viz., a drum on which the wire is wound, a journal-box for receiving the drum, and a key which fits in grooves in the journal-box to hold the drum 20 in place—all arranged and operated to tighten the wires of a fence, as hereinafter described.

My improvement is illustrated in the accompanying drawings, in which Figure 1 is a face view of a post with my improved binder 25 in position and the wire secured thereto; Fig. 2, a section on line *x* *x* of Fig. 1; Figs. 3, 4, and 5, detail views of the separate parts of the invention.

In the drawings, A represents a drum, 30 which is a rounded shank squared at one end to receive a wrench, and provided between its ends with square projections or blocks *b*.

C is a journal-box provided with sockets *d*, to receive the round ends of the shank, a 35 slot, *e*, through which the wire is passed, and grooves *ff* on both sides of the slot, to receive the key *G*. The key *G* is slotted, forming arms *h* with inclined faces, and at its front end, on the under surface, provided with lugs 40 *i*, that are adapted to hold the key in the grooves *ff* of the journal-box. The drum is provided with a hole, *j*, between the blocks *b*, through which the fence-wire is inserted.

The binder is attached to the post by means 45 of screws or nails passed through holes *l* in the journal-box. The drum is held in the journal-box by the tension of the wire.

In operation the wire is passed through the post, through the slot in the journal-box, and 50 through the hole in the drum. The drum is then turned by a wrench and the wire thereby tightened. When the desired tension is ob-

tained, the slotted key is slid under the square projections and into its place in the journal-box, whereby the binder is securely locked in 55 place and all slipping prevented.

When the drum is in place, before the key is applied, the square corners *b* are held above the bottom of the journal-box far enough to prevent their touching the journal-box. When 60 turned in winding the wire, the square edges strike the bottom of the box, which serves as a fulcrum, adding power to the leverage. The drum can be locked by the key at every quarter-revolution. 65

This binder is as applicable in the stretching of telegraph-wires as it is for the stretching of fence-wires.

Having thus described my invention, what I claim, and desire to secure by Letters Patent, is—

1. In a wire-stretcher, the combination, with the journal-box having open ended bearing sockets, of the winding-drum mounted in said bearing-sockets and provided with blocks 75 of greater diameter than its body and so formed as to bear against the wall of the journal-box when the drum is rotated, substantially as and for the purposes set forth.

2. In a wire-stretcher, the drum *A*, provided with the square central projections *b*, the journal-box *C*, provided with slot *e* and the grooves *f*, and the key *G*, having a projection adapted to fit into the said grooves of the box, whereby the drum when the wire is 85 tightened is locked and held in place, substantially as described.

3. A wire-fence binder comprising, in combination, a winding-drum, *A*, the journal-box *C*, provided with sockets *d*, to receive the ends 90 of the drum shank, a slot, *e*, through which the wire is passed, and grooves *ff* on both sides of the slot, to receive a key, and said key *G*, slotted to form arms *h*, having inclined faces on one end, and provided with lugs whereby 95 the key is adapted to fit into the grooves of the journal-box, substantially as described.

In testimony whereof I affix my signature in presence of two witnesses.

WILLIAM C. GHOLSON.
